Jack Hutchinson

By
Bollinger & Block Attorneys:

UNITED STATES PATENT OFFICE.

THEODORE A. MOORE, OF DAVENPORT, IOWA.

FLOOR-STRIP CLIP-SETTING DEVICE.

Application filed March 21, 1924. Serial No. 700,937.

My invention relates to new and useful improvements in a device for aligning and setting clips in a freshly laid concrete floor, the clips being of the usual formation used for fastening the wooden strips or sleepers to which a superimposed wooden floor is afterwards nailed.

In the past considerable trouble has been experienced in getting the clips of the type specified set into the soft concrete and to get them set in a straight line and spaced at definite intervals from each other, and the principal object of my invention resides in the provision of a device whereby a plurality of such clips may be inserted in the concrete at the same time and in such a manner that they will be in a straight line and spaced at regular intervals one from the other.

20 A further object of the invention resides in the provision of a device of the character specified wherein a plurality of clips are separately held but in which all of them will be simultaneously released for embedding them in the concrete, each of the clips being held by a pivoted catch and means being provided for operating all of the catches at the same time to release the clips.

With the above and other objects in view, 30 which will appear as the description proceeds, my invention consists in the novel details of construction, and arrangement of parts, described in the following specification and illustrated in the accompanying drawings, and while I have illustrated and described the preferred embodiments of the invention as they now appear to me it will be understood that such changes may be made as will fall within the scope of the 35 appended claims.

In the drawings:

Fig. 1 is a side elevation.

Fig. 2 is an end view.

Fig. 3 is a transverse vertical section on the line 3—3 of Fig. 1 looking in the direction of the arrows.

Fig. 4 is a top plan.

Fig. 5 is a detail showing one of the clips to be inserted into the concrete.

50 Fig. 6 is a detail view of the same clip with the arms bent in vertical position, after the clip has been embedded into the concrete.

Fig. 7 is a detail, enlarged, of the lower 55 end of one of the catches, and

Fig. 8 is a fragmental plan of one of the metal plates secured to the bottom of the beam.

In the drawings 1 indicates a beam having a vertically extending slot 2 formed 60 intermediate the ends thereof and preferably longitudinally of the center. Secured to the bottom of the beam are a plurality of plates 3, the ends of the plates being spaced apart as shown at 4 for a purpose 65 which will later appear. A notch 5 is formed in one end of each of the plates and in alignment with the slot 2 formed in the beam. A plurality of longitudinally spaced catches 6 extend through the slot 2 70 and are pivotally connected to the beam 1 at 7, the upper ends of the catches extending above the upper surface of the beam to provide handles or grips 8 and the lower ends 9 extending below the undersurface 75 of the beam and within the spaces 4 formed between adjacent ends of the plates 3. Notches 10 are formed in one edge of each of the catches 6, adjacent the lower end, and the inner wall of the notch is down- 80 wardly and outwardly inclined as shown at 11 for a purpose which will presently appear. A coiled spring 12 is provided for normally holding the lower end of each of the catches within the space 4, said springs 85 being connected to the catches at 13, adjacent the upper ends thereof, and to the beam 1 at 14.

Secured to the top of the beam 1, on one side of the opening 2, is a plate 15 and slidably mounted on the beam, on the opposite side of the slot, is a bar 16 which has secured to its upper face, and extending transversely of the beam, a plurality of projections 17, said projections overlying the 90 slot 2 adjacent the edges of the catches 6 and on the same side of said catches as the springs 12 are attached. The bar 16 is operable through a plurality of guides secured longitudinally of the beam. Each of the 95 guides comprises a vertically extending arm 18 which is secured to the side of the beam by means of the screws 19 or other suitable fasteners, a horizontal arm 20 which extends over the bar 16 and the upper surface of the beam, and the downwardly extending projection 21 which enters the slot 2.

Pivottally connected at 22 to the side of the beam 1 is a lever 23, the upper end of which extends above the top of the beam. 100

to provide the hand-hold 24. Secured to the bar 16, preferably adjacent one end thereof, by means of the rivets or other suitable fastening means 25 is a plate 26 which has the upwardly extending arm 27 pivotally connected to the lever 23 at 28.

One of the clips to be embedded in the concrete is indicated at 29 and will be positioned relative to the beam 1 as is quite clearly 10 shown in the drawings.

When the device is to be used the position of the beam is reversed so that the normally lower face thereof extends upwardly. The clips 29 are then positioned upon the beam 15 within the spaces 4, as shown, and the notched ends of the catches 6 will engage the clips and hold them in position upon the beam, it being understood that the springs 12 draw the notched ends of the 20 catches inwardly towards the clips so that the horizontal portions of the clips will be held between one end of the plates 3 and the ends of the catches, one edge of the longitudinal portions of the clips being received 25 in the notches 10 of the catches, the inclined portions 11 extending slightly beneath the horizontal portions of said clips. With the clips thus held the device is again inverted to its original position so that the clips 30 depend therefrom. The beam is lowered so that the clips are embedded in the soft concrete and are released from the beam by operating the lever 23. When the lever 23 is operated it slides the bar 16 so that the 35 projections 17 engage the edges of the catches adjacent their upper ends thereby moving the lower end of the catches away from the clips and allowing them to be released from the beam and held in the concrete. When 40 the catches are moved to release the clips the lower ends thereof will be received in the notches 5 of the plates 3. It will be understood that when the catches are released that the springs 12 are placed under 45 tension and when the lever 23 is moved into its original position the catches will automatically be returned to their normal or original positions. Of course, in applying the clips to the beam the catches are operated by engaging the hand-holds 8.

From the above it will be seen that I have provided a device whereby floor strip clips may be embedded in soft concrete at uniform intervals and in a straight line and that I 55 have provided an individual catch or holder for each clip on the beam, said catches or holders being operable individually to apply the clips to the beam and operable in unison for releasing the clips.

Having fully described my invention what I claim as new and desire to secure by Letters Patent is:

1. A device of the character described for setting clips including a support, plates secured to the support with their adjacent ends

spaced to form recesses to receive the clips, and members connected to the support and engageable with the clips for holding them in position.

2. A device of the character described for 70 setting clips comprising a support, a plurality of catches pivotally connected to the support and engageable with the clips for positioning them upon the support, and means for operating the catches simultaneously to release the clips.

3. A device of the character described for 80 setting clips comprising a support, and a plurality of catches pivotally connected to the support and engageable with the clips for positioning them upon the support, each catch engaging a separate clip.

4. A device of the character described for 85 setting clips comprising a support, a plurality of catches pivotally connected to the support and engageable with the clips for positioning them upon the support, the catches being adapted for individual operation for attaching the clips to the support, and means for simultaneously operating the 90 catches for releasing the clips.

5. A device of the character described for 95 setting clips comprising a support, a plurality of catches movably connected to the support and adapted to engage the clips, a sliding bar carried by the support, and means for operating the sliding bar to operate the catches simultaneously.

6. A device of the character described for 100 setting clips comprising a support, a plurality of catches movably connected to the support and adapted to engage the clips, a slide- 105 able member carried by the support, means for operating the slideable member, and means carried by the slideable member and engageable with the catches for operating the same upon movement of the slideable member.

7. A device of the character described for 110 setting clips comprising a support, a plurality of catches movably connected to the support and adapted to engage the clips for positioning them upon the support, a slide- 115 able member carried by the support and extending longitudinally thereof, means for operating the slideable member relative to the support, and transversely extending members carried by the slideable member and engageable with the catches for operating the same upon movement of the slideable 120 member.

8. A device of the character described for 125 setting clips comprising a support having a longitudinally extending opening therein, a plurality of catches extending through the longitudinally extending opening and pivotally connected to the support for engagement with the clips to position them upon the support, and means carried by the support for operating the catches.

9. A device of the character described for setting clips comprising a support having a longitudinally extending opening therein, a plurality of catches extending through the opening and pivotally connected to the support for engagement with the clips, said catches being adapted for individual operation for positioning the clips upon the support, and means carried by the support and extending transversely of the opening therein for engaging the catches and operating the same in unison for releasing the clips from the support.

10. A device of the character described for setting clips comprising a support, a plurality of catches movably connected to the support and adapted to engage the clips, guides secured to the support, a member 15 slideable in the guides and engageable with the catches for operating the same, and means for operating the slideable member.

11. A device of the character described for setting clips comprising a support having a longitudinally extending opening 25 therein, longitudinally extending plates secured to the bottom of the support, the adjacent ends of the plates being spaced apart, catches extending through the opening in the support and pivotally connected to the support with their lower ends received in the spaces between the ends of the adjacent plates and adapted to engage the clips for 30 positioning them upon the support, and

means for operating the catches to release the clips.

12. A device of the character described for setting clips comprising a support having a longitudinally extending opening therein, a plurality of longitudinally spaced plates secured to the bottom of the support, each of 40 the plates having a notch in one end in alignment with the opening in the support, a plurality of catches extending through the opening in the support and pivotally connected to the support with their lower ends 45 normally received in the spaces between the ends of the plates to engage the clips for positioning them upon the support, and means for operating the catches to release the clips from the support, the ends of the 50 catches when operated passing into the notches formed in the ends of the plates.

13. A device of the character described for setting clips comprising a support having recesses therein for receiving the clips, 55 catches pivotally connected to the support and engageable with the clips for securing them to the support, said catches being adapted for individual operation when positioning the clips upon the support, and 60 means for simultaneously operating the catches for releasing the clips from the support.

In testimony whereof I affix my signature.

THEODORE A. MOORE.
